(57) **CLAIM**

The ornamental design for a digital camera, as shown and described.

DESCRIPTION

FIG. 1 is a perspective view of a digital camera, showing our new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

The evenly spaced broken lines shown in the drawings are for the purpose of illustrating portions of the digital camera that form no part of the claimed design. The dot-dash broken lines in the drawings show an unclaimed boundary of the claimed design.
